UNITED STATES PATENT OFFICE.

JOHN OSCAR MALMQUIST, OF SAN FRANCISCO, CALIFORNIA, ASSIGNOR TO AMERICAN CAN COMPANY, OF SAN FRANCISCO, CALIFORNIA, A CORPORATION OF NEW JERSEY.

OVAL-GEAR DOUBLE-SEAMER HEAD.

Application filed June 21, 1926. Serial No. 117,303.

The present invention relates to improvements in machines for applying ends to cans by what is commonly known as the "double-seaming" process.

5 The principal object of the invention is to provide a machine for double-seaming so-called oval, or elliptical, cans without causing any appreciable slippage between the seaming rolls and the can. A secondary object is to provide such a machine of simple 10 construction, and in which the seaming rolls can be made inexpensively.

It is customary in the art to double-seam elliptical cans in a machine in which the seaming rolls are both revolved around the can and rotated upon their own axes at a constant speed, as in seaming circular cans. However, on account of the elliptical contour of the seam and the constant rotative 20 speed of the rolls, there is considerable slippage between the peripheries of said rolls and the seam at certain portions of the orbit. This slippage is troublesome, and frequently results in rubbing the tin plating off the 25 metal of the seam, leaving the bare iron exposed to rust. Such slippage can be reduced slightly by making the rolls cam-shaped, but this expedient is costly, and does not lessen the slippage enough to be satisfactory.

30 The present invention provides means for rotating the seaming rolls at a varying rate of speed corresponding almost exactly to their peripheral travel upon the seam, so that no appreciable slip occurs. Moreover, the rolls, 35 although eccentrically mounted, can be made circular, thereby materially reducing their cost as compared to the cam-shaped rolls mentioned above. The preferred means by which the invention is carried out is herein described and illustrated as embodied in a 40 well known type of double-seamer in which a pair of seaming rolls are carried in a revolving head, and caused to travel, in an epicyclic path, about a stationary can. It is to be understood, however, that the principles of 45 the invention may be embodied in machines of other types and for other uses, and that the form, arrangement and construction of the several parts hereinafter described may be varied, within the limits of the claims here- 50 to appended, without departing from the spirit of the invention as set forth in said claims.

With this in view a preferred embodiment 55 of the invention will now be described fully

with reference to the accompanying drawings, wherein—

Fig. 1 is a part sectional elevation of a well known type of seaming head with the present invention embodied therein. 60

Fig. 2 is a bottom plan view, the can and its holder being omitted.

Fig. 3 is a top plan view, partly in section.

Fig. 4 is a partly broken horizontal section taken on the line 4—4 of Fig. 1. 65

The drawings show only the chuck and rotary head of a double-seamer of a well known type, the remaining portions of the machine being omitted as forming no part of the present invention. Referring for the moment to 70 Fig. 1, the numeral 1 designates an oval or elliptical can, having an end or cover whose flange 2 is to be seamed. The can rests upon a suitable holder 3, by which it is raised to bring its end or cover into contact with a 75 chuck 4, said chuck being elliptical, as shown in Fig. 2, to seat securely upon the can end. The chuck 4 is secured by a set screw 5, Fig. 1, upon the lower end of a fixed vertical shaft 6.

80 7 is an ejector extending through said shaft and operated in any suitable manner, not shown.

85 Journaled upon the shaft 6 is a rotatable gear 8 formed with peripheral teeth 9—Figs. 1 and 3, and said gear has mounted in it, on trunnions 10, a pair of journal blocks 11 in which are carried the seaming roll spindles 12. The trunnions 10 allow said spindles to swing radially at their lower ends. Thrust 90 collars 13, above the journal blocks 11, support the weight of said spindles.

95 Journaled upon the shaft 6, below and secured to the gear 8 is a hub 14, Fig. 1, which has at its lower end, immediately above the chuck 4, a spider 15 having oppositely disposed slots or guide ways 16, Figs. 1 and 2. Bearing members 17, in which the spindles 12 are journaled, are slideable, radially, in said 100 guide ways, thus guiding the lower ends of said spindles in their swinging movement. Adjustable stop screws 18 limit the outward movement of said spindles.

105 The spindles 12 carry upon their lower ends the seaming rolls 19. These rolls are circular, as shown in Fig. 2, and are eccentrically mounted upon the spindles to cause them to follow the elliptical seam of the can and its end. They are provided with the usual seaming or curling grooves 20, which 110

are so formed as to operate consecutively to complete the seam, i. e. one roll is first brought into contact with the flange 2 to initially curl the seam, and the other roll subsequently completes it, all in the usual manner.

The spindles 12 are swung in and out, likewise in the usual manner, to bring their rolls 19 into contact with the flange 2 at the proper times, by levers 21, Fig. 1, fulcrumed at 22 upon opposite sides of the hub 14. The lower ends of said levers are connected by links 23 with the spindle journal members 17. Nuts 24 are provided upon the ends of said links for adjustment. The upper ends of the levers 21 carry rollers 25 which bear against and follow the face cams 26 secured upon transverse rotating shafts 27. There are two such shafts 27, parallel with each other, each having a cam 26 upon each end. There are also two levers 21, operating in unison, for each spindle, as shown in Fig. 4. The two shafts 27 are inter-connected by gears 28, and one of said shafts is driven, in the proper timed relation, by a worm-wheel 29 which meshes with a worm 30 formed upon the fixed central shaft 6. The cam shafts 27 and levers 21 are carried upon the hub 14, and all revolve together around the fixed shaft 6.

The hub 14 has two opposite arms 31, Figs. 3 and 4, equally spaced between the spindles 12, which extend upwardly and are secured to the gear 8 by bolts 32, so that said hub and said gear are rigidly connected together to form the complete head.

The spindles 12 are rotated upon their axes, as the head revolves about the shaft 6, by eccentric pinions 33, Figs. 1 and 4, which mesh with an elongated or elliptical fixed gear 34 secured upon said shaft. The elliptical gear 34 has its pitch line approximately corresponding, in contour and size, to the flange 2 of the can 1, and the pinions 33 similarly correspond to the seaming rolls 19. Therefore the spindles 12, and their rolls 19, are rotated upon their axes with a varying speed corresponding to the natural rolling contact of said rolls about the flange 2, so that there is practically no slippage between said rolls and said flange. It is understood, of course, that the diameter and eccentricity of the rolls 19 and the pinions 33 are properly related to the characteristics of the curve of the can flange 2 and the gear 34.

In the operation of the device, the can 1, with its end or cover loosely resting upon it, is placed upon the holder 3, and raised thereby to bring said end or cover into firm contact with the chuck 4. The holder 3, the can 1 and its end or cover, and the chuck 4 do not rotate, but the revolution of the entire seaming head about the stationary shaft 6 causes the seaming rolls 19 to be rotated upon their own axes. The revolution of the head

also causes the seaming roll spindles 12 to be swung at their lower ends, through the agency of the cams 26 and the levers 21, so that the rolls 19 are brought into contact with the flange 2 of the can and consecutively and for the proper duration of time to crimp or curl said flange into a seam in the usual manner.

During the seaming process, the peripheral grooves 20 of the rolls 19 follow the flange 2 of the can end accurately, without lateral movement of the spindle 12, on account of the size and eccentricity of said rolls with relation to contour of the flange 2; and said rolls follow said flange without slipping thereupon, on account of their varying rotative speed produced by the action of the eccentric pinions 33 in traveling about the stationary elliptical gear 34.

I claim:—

1. In a can seaming machine, a chuck member and a head member, one of said members being rotatable, and said chuck member being adapted for engagement with the end of a non-circular can; a seaming roll carried by the head member and adapted for rolling contact with the periphery of the can; and means including a gear having an eccentric axis for rotating said seaming roll with a varying speed corresponding to its natural rotation in traveling around and in contact with the periphery of the can.

2. In a can seaming machine, a chuck member and a head member, one of said members being rotatable, and said chuck member being adapted for engagement with the end of an elliptical can; a seaming roll carried by the head member and adapted for contact with the periphery of the can; and an elongated gear for rotating said seaming roll eccentrically about its own axis with a varying speed adapting it to roll without slipping around the periphery of the can.

3. In a can seaming machine, a chuck member and a head member, one of said members being rotatable, and said chuck member being adapted for engagement with the end of a non-circular can; a gear associated with said chuck member, said gear of elongated form having substantially the same shape and size as the circumference of said can; a seaming roll carried by the head member and adapted for rolling contact with the periphery of the can; and a pinion associated with said seaming roll and adapted to mesh with said gear, said pinion having substantially the same shape and size as said seaming roll.

4. In a can seaming machine, a chuck member and a head member, one of said members being rotatable, and said chuck member being adapted for engagement with the end of a non-circular can; a gear associated with and spaced above said chuck member, said gear having substantially the same shape and size as the circumference of said can; a spindle

rotatably carried in said head member and swingable relative to the axis of the head member; a seaming roll eccentrically mounted upon the lower end of said spindle and adapted for rolling contact with the periphery of the can; a pinion eccentrically mounted upon the upper end of said spindle and adapted to mesh with said gear, said pinion having the same shape and size as said seaming roll; 10 and means for moving said spindle to carry said seaming roll into and out of operative relation with the can without disengaging said pinion from said gear.

5. In a can seaming machine, a chuck member and a head member, one of said members being rotatable, and said chuck member being adapted for engagement with the end of a non-circular can; a seaming roll carried by the head member and adapted for rolling contact with the periphery of the can; means including an elongated gear and a pinion having an eccentric axis for rotating said seaming roll with a varying speed corresponding to its natural rotation in traveling around 20 and in contact with the periphery of the can; and means for moving said seaming roll bodily toward and away from the can to carry it into and out of operative contact therewith.

6. In a double-seamer, a chuck member and 30 a head member, one of said members being rotatable, and said chuck member being adapted for engagement with the end of a non-circular can; a pair of seaming rolls carried by the head member and adapted for 35 rolling contact with the periphery of the can; means for rotating said rolls with varying speed corresponding to their natural rotation in traveling around and in contact with the periphery of the can; and means for successively moving said rolls bodily into and out of operative contact with the can to perform 40 successive first and second seaming operations thereupon.

7. In a can seaming machine the combination of a fixed shaft, an elongated gear fixed thereon, pivotally hung spindles swingable toward and from the axis of said shaft, pinions eccentrically fixed on said spindles and meshing with said gear, seaming rolls carried by said spindles, means for rotating said spindles, pinions and rolls around the fixed shaft, and means for holding a can and cover 50 to be seamed by said rolls.

In testimony whereof I have signed my 55 name to this specification.

JOHN OSCAR MALMQUIST.
